COPY HOLDERS

Harry E. Lucas, Grand Rapids, Mich.

Application November 18, 1954, Serial No. 469,735

2 Claims. (Cl. 312—184)

This invention relates to filing devices and more particularly to a device for filing copy in a newspaper office in such a manner that it is both easily located and readily removable.

No successful system for filing copy such as the original copy and the proofs of newspaper material, particularly advertising, has ever been developed. Heretofore this material has been stored by being stabbed on a hook. With this arrangement, the copy is substantially impossible to locate because all the items are crowded together. The individual items are practically impossible to separate sufficiently to ascertain which is which. Further, in separating the copy to find one particular piece, the copy becomes torn and damaged and often is lost. Further, if the particular piece of copy desired is deep on the hook, all of the pieces of copy in front of it must be removed in order to obtain it. This results in further damage to the material.

My invention eliminates this difficulty by making it possible to quickly and easily identify each piece of copy. Once identified, the copy may be quickly removed without the necessity of removing any other piece of copy and without damage to the other pieces of copy. This invention accomplishes these purposes by a simple, relatively inexpensive and durable mechanism.

Other objects and purposes of my invention will be immediately seen by those acquainted with the filing of printed newspaper material upon reading the following specification and the accompanying drawings.

In the drawings:

Fig. 1 is an oblique view of a cabinet designed to incorporate my invention.

Fig. 2 is an oblique plan view of one section of the cabinet illustrating a typical example of my invention.

Fig. 3 is a fragmentary, side elevation view of the copy holder mechanism of my invention.

Fig. 4 is an enlarged, fragmentary, oblique view of the mounting for one portion of my copy holder.

Fig. 5 is an enlarged, fragmentary, plan view of the mount appearing in Fig. 4.

Fig. 6 is an enlarged, fragmentary, side elevation view of the copy holding rod in open position.

Fig. 7 is an enlarged, fragmentary, plan view of the copy holding rod in closed position.

In executing the objects and purposes of my invention, I have provided a rod divided in half with both ends being firmly mounted. The forward portion of the rod is permanently fixed while the rearward portion of the rod may be pivoted about its mounting. The ends of the rod at the point where they are split are designed to overlap so that the fixed front portion of the rod will support the front end of the pivoted rear portion of the rod which is normally held in engagement with the front portion of the rod by a spring.

Referring specifically to the drawings, the numeral 1 refers to a cabinet having a lower storage portion 2 and an upper filing portion 3. The cabinet is preferably divided into a number of sections, each section designed

2

to store the copy for one particular day. Each section is equipped with a rod means for storing the copy material. This means is the basis of my invention. Since each of the sections is identical in this respect, it is only necessary to describe one of the sections such as is illustrated in Fig. 2.

The cabinet 1 is of such height that the operator may view the contents from above. For this purpose the top of the cabinet is open. The cabinet has a rigid back 10 panel 4 and a rigid front panel 5. These panels may be of any suitable material such as wood, metal or plastic. To the front panel 5 there is secured the forward portion 6 of the filing rod 7. The forward rod portion 6 is secured to a plate 8 which in turn is mounted to the front panel 5 by suitable means such as screws. The forward rod portion 6 is permanently fixed to the plate 8 and thus is stationary. The rearward portion 10 of the filing rod 7 is pivotally mounted to the back panel 4 by means of the ball and socket 11 and 12 respectively. The ball 11 is rigidly affixed to the end of the rearward rod portion 10. The socket 12 has associated with it a mounting plate 13 adapted to be rigidly affixed to the back panel 4 by suitable means such as the screws 14.

The rearward portion 10 of the filing rod 7 is urged 25 downwardly by a spring 15, one end of which is secured to the rearward rod portion 10 and the other end to the back panel 4 at a point below the socket 12.

The filing rod 7 is split at 20 adjacent its center, thus forming the forward portion 6 and the rearward portion 10. The split 20 is best illustrated in Figs. 6 and 7. The forward rod portion 6 is provided with a wedge-shaped and forwardly inclined tongue 21 while the rearward rod portion 10 is provided with a rearwardly and downwardly sloped pocket 22 designed to firmly seat the tongue 21. The shape of the tongue 21 and of the pocket 22 cause the forward rod portion 6 to support the rearward rod portion 10 and limit its downward movement. The tongue and pocket should be made to relatively close tolerances so that when the two are engaged and the rods aligned they form a smooth joint having no tendency to snag the copy papers as they are moved across the joint.

When this invention is applied to a newspaper office, the copy 30 is frequently a full size page of a newspaper.

45 This paper is folded in four and an identification tag 31 is secured to it. The identification tag is preferably of a fairly sturdy and rigid paper material and is provided with a hole 32 for receiving the filing rod 7. The tags 31 are designed to stand a substantial distance above 50 the rod. Identifying information is placed on the upper portions of these tags where it is readily accessible and visible to an operator searching through the file from above. To locate a particular item of copy, the operator, instead of having to inspect the copy itself, identifies it 55 by the information placed on the tag. Further, the tag, being of a somewhat heavier material, provides support for the copy and takes the normal wear incident to the copy being pushed back and forth along the rod 7.

When a piece of copy is to be removed, the operator 60 searches through the tags to identify the piece of copy. Then that piece of copy is moved toward the split joint 20 in the rod. The joint is opened by pulling the rear rod portion 10 upwardly as illustrated in Fig. 6 and the piece of copy slipped through the resulting gap. Upon release of the rearward rod portion 10, it automatically 65 reengages the front rod portion 6, locking the remaining copy in place. Thus, any piece of copy no matter where it may be located along the rod 7 may quickly and easily be removed through the split 20 without necessitating the removal of any other piece of copy on the rod. The rod 7, of course, is designed to be long enough to not only hold the expected quantity of copy but to allow for

considerable freedom of movement of the copy along the rod in order that each item of copy may be aligned with the split 20 without the necessity of removing any other items of copy.

I have described my invention with the stationary portion of the rod forward. This is a preferred arrangement because it permits the copy to be removed by a forward movement through the split 20. However, it will be recognized that the rod portions can be reversed and the movable rod portion placed in the forward position.

It will be recognized that other modifications of my invention may be made without departing from its principles. Such modifications are to be considered as included in the hereinafter appended claims unless these claims by their language expressly state otherwise.

I claim:

1. A cabinet for filing thin, sheet-like articles comprising: side panels, a rigid vertical front panel, a rigid vertical back panel, the top edge of said panels terminating at a level sufficiently low to enable an average height person to view the contents from above; the top marginal edges of said panels defining an unobstructed opening extending therebetween for receiving said articles; a stationary arm secured to one of said front or rear panels and extending toward said other front or rear panel; a movable arm pivotally secured to said other panel for vertical movement, said movable arm extending toward said other panel and adapted to engage and

interfit the free end of said stationary arm; said movable and stationary arms being axially aligned when their ends are interfitted.

2. A cabinet for filing thin, sheet-like articles comprising: side panels, a rigid vertical front panel, a rigid vertical back panel, the top edge of said panels terminating at a level sufficiently low to enable an average height person to view the contents from above; the top marginal edges of said panels defining an unobstructed opening extending therebetween for receiving said articles; a pointed stationary arm secured to said front panel and extending toward said rear panel; a movable arm pivotally secured to the back panel for vertical movement; said movable arm extending toward said front panel and adapted to engage and interfit the free end of said stationary arm; said movable and stationary arms being axially aligned when their ends are interfitted.
